UNITED STATES PATENT OFFICE.

FREDERICK W. KOLB, OF LA CONNER, WASHINGTON.

MEANS FOR CLEANING AND OILING THE SKIDS OF SKIDWAYS.

1,137,867.

Specification of Letters Patent.

Patented May 4, 1915.

Original application filed June 20, 1914, Serial No. 846,411. Divided and this application filed November 2, 1914. Serial No. 869,905.

To all whom it may concern:

Be it known that I, FREDERICK W. KOLB, a citizen of the United States, residing at La Conner, in the county of Skagit and State 5 of Washington, have invented certain new and useful Improvements in Means for Cleaning and Oiling the Skids of Skidways, of which the following is a specification, reference being had to the accompanying 10 drawings.

This application is a division of an application filed by me for skid cleaners and oilers, on June 20, 1914, Serial No. 846,411, and this invention relates to devices for 15 cleaning and lubricating the skids of skidways which are used in lumber camps and upon which logs are drawn to railroad sidings or to banks of streams.

In the use of skidways of the character 20 above stated a train of logs is drawn along the skidway by any suitable means, these logs being connected to a carriage and traveling one after the other in line with each other. It is necessary as the logs are drawn 25 along the skidway that oil or other lubricant be applied to the skids on a line with the logs so that the logs may travel easily over the skids. If bark, chips or like extraneous matter has accumulated upon the skids, and 30 then if oil be applied to the skids, it will be applied upon the chips or bits of bark and the first log of the train striking these chips will knock them off, and as a consequence the skid will not be oiled. It is the primary 35 object of my invention to provide a skid cleaning and lubricating device which will act first to clear away chips or dirt from the middle of the skid log and then immediately thereafter apply oil thereto, the oil being 40 applied automatically as the oiling device arrives over a skid log, the oiling mechanism being held inoperative between the skid logs so that no oil may be wasted.

It is a further object of my invention to 45 provide a carriage having the form of a sled with runners of such length as to bridge the space between the skid logs, this carriage supporting the cleaning mechanism and the oil applying mechanism and being 50 also provided with means whereby a train of logs may be drawn behind it in the usual manner.

Other objects will appear in the course of the following description:

55 With this and other objects in view as

will become more fully apparent as the description proceeds, my invention consists in the novel construction, combination, and arrangement of parts, to be hereinafter more fully described, claimed, and illustrated in 60 the accompanying drawing, in which—

Figure 1 is a side elevational view of my device; Fig. 2 is a vertical sectional view of the air pump on line 2—2 of Fig. 1; Fig. 3 is a detail view in plan showing the air 65 pump; Fig. 4 is a fragmentary elevational view showing the manner of connecting one of the lift bars of the cross head for operating the air pump to the cylinder of the pump; and Fig. 5 is a vertical sectional view 70 of a portion of the cylinder and piston of the air pump showing the location of one of the valve openings therein.

Referring more particularly to the drawing, the numeral 1 designates the skids of a 75 skidway, upon which my improved device is adapted to slide, the device including a pair of spaced parallel runners 2 upon the upper edges of which, at their forward ends, is secured a plurality of cross bars or timbers 3 which connect the runners together, and mounted upon the bars 3 is a platform 4. Secured upon the platform 4, adjacent 80 its forward end, is a base 5 which is provided with an upstanding internally threaded neck 6, the neck receiving the lower threaded end of the air pump cylinder 7, and the base having a discharge opening 8 formed centrally therein. The cylinder 7 is provided with a removable cover 9, the 85 cover having depending spring catches 10 connected thereto which are adapted for engagement with outwardly extending lugs 11 formed on the cylinder adjacent its upper end, whereby the cover is removably connected to the top of the cylinder. The cover is provided with a central opening 12, and a guide plate 13 is arranged across the top and is also provided with an opening therein which communicates with the opening 12 in 90 the cover, and a piston rod 14 is passed through the registering openings, the lower end of the piston rod being threaded and having a piston 16 detachably mounted thereon. Connected to the upper end of the 95 piston rod which projects above the cylinder, is a cross head 17, the opposite ends of which project beyond the cylinder at diametrically opposite points, and pivotally connected to the opposite ends of the cross 100 105 110

head are vertically disposed lift bars 18 which extend downwardly through slots 19 in the opposite ends of the guide plate 13, and are slidably disposed through guide boxes 20 connected to the periphery of the cylinder at diametrically opposite points thereof, intermediate of its ends.

- Secured to the upper face of the platform 4, forwardly of the cylinder 7, are spaced 10 bearing members 21 in which the opposite ends of a supporting rod 22 are mounted, and pivotally supported upon the opposite ends of the rod between the members 21 are the forwardly and upwardly extending arms 15 23 of a pair of angular levers. These forwardly extending arms 23 extend downward to a point below the runners so as to be disposed in the path of the skids and the levers then extend upwardly and rearwardly so as 20 to provide the rear arms 24 which are operatively connected to the pump, as will be later stated. The arms 23 of the levers are each provided adjacent their forward ends with a plurality of openings 26 so that the 25 levers may have the rod 22 which forms the pivotal support of said levers passed through any one of said openings and thereby regulate the distance to which the levers shall project below the runners. The forward and rear ends of the levers project 30 through slots in the platform, and the inner ends of the levers are pivotally connected at their extremities to the lower ends of connecting rods 27, the upper ends of the connecting rods being pivotally mounted upon 35 studs 28 which project from sleeves 29, the sleeves being mounted upon the lift bars 18 and being secured thereupon in adjusted position by the set screws 20 which project 40 through the sleeves into engagement with the lift bars. It will be seen that when the arms 23 are raised, due to their engagement with a skid, the cross head 17 is also raised, thereby moving the piston 16 upwardly 45 within the cylinder. To return the piston to its lowermost position and to normally hold the same in the lower end of the cylinder, any desired number of weight disks 31 may be secured upon the piston rod above the 50 piston.

The cover 9 is provided with a plurality of air openings 32 and the piston 16 also has openings 32^a formed therein, the piston having flap valves 33 secured to its under face, the 55 valves 33 normally closing the openings 32^a in the piston, and being forced away from the openings as the piston is raised within the cylinder to allow air to pass through the piston into the space between the upper face 60 of the base of the cylinder and the lower face of the piston. It will be seen that as the piston 16 is lowered, the flap valves 33 are forced against the lower face of the piston to close the openings therein, and the air 65 found in the compression space between the

base 5 and the under face of the cylinder is forced through the opening 8 against the upper face of the skid to clean the same. A raised ring 34 is formed on the upper face of the base, the ring having a groove 35 formed therein to receive a rubber or other flexible ring 36, against which the piston will strike at the limit of its downward movement, this ring forming an air tight chamber between itself and the cylinder, 70 thus alleviating the jar which would otherwise be imposed upon the base. Mounted on the platform 4, rearwardly of the air pump is an oil pump generally designated by the numeral 37, which is operated by a lever 38, 75 the lever, pump, and the intermediary mechanism being fully described in the application filed by me, Serial No. 846,411.

The operation of my device is as follows:—The draft animals are driven forwardly to move the logs over the skids in the usual manner, the platform upon which my improved mechanism is mounted being connected to the draft animals forwardly of the foremost log. It will be seen that when the arm 23 engages a skid, the lever is raised, which operation raises the piston 16 in the cylinder 7 of the air pump, thereby drawing air into the chamber below the piston, and that when the lever passes over the skid, the weights 31 force the piston downwardly, thereby discharging air from the opening 8 against the top of the skid to blow any dirt which might be upon the skid off the same.

From the above description, taken in connection with the accompanying drawing, it will be seen that I have provided a simple mechanism for cleaning the skidways, and that this mechanism used in connection with the oil pump 37 serves to provide a mechanism which will thoroughly clean and oil the skids in advance of the logs, so that the logs may easily slip along the skidway with minimum resistance.

It is to be noted that the cleaning device is really part of the oiling mechanism, for the reason that there would be no object in cleaning the skids of chips and dirt were it not that oil was to be applied thereto and were it not that if oil were applied to the chips and dirt the following log would scrape the foreign matter from the log and leave the log unlubricated.

Having thus fully described my invention, what I desire to claim and secure by Letters Patent is:—

1. A device for cleaning the skids of skidways including a carriage, an air pump carried upon the carriage, and means for automatically actuating the air pump to apply air to each successive skid as the device is drawn along the skidway.
2. A device for cleaning the skids of skidways including a carriage, and automati- 130

- callly operated means carried upon the carriage to clean each successive skid as the device is drawn along the skidway.
3. A device for cleaning the skids of skidways comprising a carriage, an air pump carried upon the carriage, actuating means operatively connected to said pump and normally disposed below the carriage to engage each successive skid as the device is drawn over the skidway, whereby the pump may be actuated to force a quantity of air upon each skid. 70
4. A device for cleaning the skids of skidways comprising a carriage, an air pump connected to the carriage, actuating means connected to the air pump and normally disposed below the carriage to engage each successive skid as the device is drawn along the skidway, and means for regulating the volume of air applied to each skid. 75
5. A device for cleaning the skids of skidways including a supporting frame, runners upon which the frame is supported, an air pump carried upon the frame, and an actuating means for the pump including a lever having an arm extending below the runners and adapted to engage successive skids. 80
6. A device for cleaning the skids of skidways including runners, air pumping apparatus mounted thereon, and means disposed below the runners in a position to be engaged by successive skids operatively engaged with the air pump to actuate the latter. 85
7. A device for cleaning the skids of skidways including runners, an air pump mounted upon the runners and including a cylinder having a discharge nozzle at its lower end, an air compressing piston movable within the cylinder, means operatively connected to the piston and depending below the runners in a position to be engaged by successive skids, said means operating to shift the piston in one direction, and means acting to shift the piston in the opposite direction. 90
8. A device for cleaning the skids of skidways including runners adapted to travel over the skids, an air pump mounted upon the runners and including a pump cylinder, a piston operating the pump cylinder having a piston rod, an angular lever pivotally supported at its upper end having a depending portion normally projecting below the runners and adapted to be engaged by successive skids, links operatively connecting said lever to the piston rod of the pump whereby to raise said piston upon an upward movement of the lever in engagement with the skid, and removable weights resting upon the piston adapted to depress the piston when the lever has been released. 95
9. A device for cleaning the skids of skidways including runners, an air pump carried upon the runners, angular levers disposed in advance of the air pump, each lever including an upwardly and forwardly directed arm and an upwardly and rearwardly directed arm, the forward arms of the levers being pivotally supported at their upper ends, and links operatively connecting the rearward arms of the levers to the air pump, said air pump having a downwardly directed discharge nozzle. 100
10. A device for cleaning the skids of skidways including runners, air pumping mechanism mounted upon the runners and including a cylinder having a downwardly directed discharge nozzle, actuating levers disposed forward of the pump, each of said levers having an upwardly and forwardly directed arm and a rearwardly and upwardly directed arm, the last named arms being operatively connected to the pumping mechanism, bearing members operatively supported upon the runners and each having a plurality of bearing notches, and a pivotal shaft upon which the forward ends of the levers are mounted, said shaft being engageable in any one of the notches in the bearing members. 105
11. A device for cleaning the skids of skidways including runners, air pumping mechanism mounted upon the runners, and a lever for actuating the air pumping mechanism, said lever being angular in form having an upwardly and rearwardly extending arm and an upwardly and forwardly extending arm, the last named arm being formed with a plurality of perforations, a pivot rod passing through any one of said perforations, and a bearing member supporting the pivot rod whereby the lever may be vertically adjusted. 110
12. A device for cleaning the skids of skidways including runners, air pumping mechanism mounted upon the runners including a cylinder, a piston rod, a downwardly extending guide rod operatively connected to the piston rod, a lever pivotally mounted at one end and normally depending below the runners, and a link connecting the lever with said guide rod, the connection between the guide rod and said lever including a sleeve adjustable upon the rod. 115
13. A device for cleaning and oiling the skids of skidways including a carriage, means mounted at the middle of the carriage for cleaning successive skids, and means mounted at the middle of the carriage behind the first named means for applying oil to successive skids, said oil applying means being inoperative between successive skids. 120
14. A device for cleaning and oiling the skids of skidways including a carriage, means mounted upon the middle of the carriage for cleaning successive skids, normally inoperative means for applying oil to successive skids mounted at the middle 125
- 65 ways including runners, an air pump carried

of the carriage and behind the first named means, and means adapted to be actuated by contact with successive skids and operatively connected to the oil applying means, said last named means automatically rendering the oil applying means intermittently operative upon the engagement of the last named means with a skid.

15. A device for cleaning and oiling the skids of skidways including a carriage, an oil container mounted upon the carriage, means controlling the emission of the oil from the container onto a skid, means mounted in advance of the container and adapted to engage with successive skids, said means when so engaged actuating the controlling means to permit the emission of oil, and means disposed in advance of and in line with said oiling means adapted to 20 clean successive skids.

Copies of this patent may be obtained for five cents each, by addressing the "Commissioner of Patents, Washington, D. C."

16. A device for cleaning and oiling the skids of skidways including a carriage having laterally disposed runners, means connected with the carriage for hauling a train of logs behind the carriage midway of said runners, means mounted upon the middle of the carriage for cleaning successive skids, and means mounted at the middle of the carriage behind said first named means and in line with the longitudinal axes of the logs hauled behind the carriage for applying oil to successive skids, said oil applying means being inoperative between successive skids.

In testimony whereof I hereunto affix my signature in the presence of two witnesses.
